[57] CLAIM

The ornamental design for a microwave oven, as shown and described.

DESCRIPTION

FIG. 1 is a front elevational view of a microwave oven, showing our new design;

FIG. 2 is a bottom plan view thereof;

FIG. 3 is a side elevational view, the opposite side being a mirror image thereof;

FIG. 4 is a top plan view thereof;

FIG. 5 is a rear elevational view thereof.

*FIG. 1**FIG. 2**FIG. 3**FIG. 4**FIG. 5*
